DESIGN FOR A CARD TABLE ATTACHMENT

Archie Gerry Watt, Allentown, Pa.

Application August 5, 1933. Serial No. 48,931

Term of patent 3½ years

To all whom it may concern:

Be it known that I, ARCHIE GERRY WATT, a citizen of the United States, residing at Allentown, in the county of Lehigh and State of Pennsylvania, have invented a new, original, and ornamental Design for a Card Table Attachment, of which the following is a specification, reference being had to the accompanying drawing, forming part thereof.

The single figure is a perspective view of a card table attachment, showing my new design.

I claim:—

The ornamental design for a card table attachment as shown.

ARCHIE GERRY WATT.
